US00D971434S

(12) **United States Design Patent** (10) Patent No.: **US D971,434 S**
Drüssel et al. (45) Date of Patent: **** Nov. 29, 2022**

(54) **RESERVOIR FOR DRUG DELIVERY DEVICE**(71) Applicant: **Sensile Medical AG**, Olten (CH)(72) Inventors: **Marco Drüssel**, Fulenbach (CH);
Christian Schmid, Aarau (CH); **Ilona Julianna Troll**, Baden (CH); **Peter Christen**, Obergerlafingen (CH);
Marika Buratti, Aarau (CH)(***) Term: **15 Years**(21) Appl. No.: **35/511,005**(22) Filed: **Jun. 22, 2020**(80) **Hague Agreement Data**Int. Filing Date: **Jun. 22, 2020**Int. Reg. No.: **DM/209274**Int. Reg. Date: **Jun. 22, 2020**Int. Reg. Pub. Date: **Dec. 25, 2020**(30) **Foreign Application Priority Data**

Dec. 24, 2019 (CH) 145092

(51) LOC (13) Cl. **24-01**

(52) U.S. Cl.

USPC ..... **D24/224**(58) **Field of Classification Search**USPC D24/113, 130, 224; D10/46.2, 96, 101
CPC A61M 5/14248; A61M 2005/14252

Primary Examiner — Darcey E Gottschalk

(57) **CLAIM**

The ornamental design for a reservoir for drug delivery device, as shown and described.

DESCRIPTION

1. Reservoir for drug delivery device

1.1 : Perspective

1.2 : Front

1.3 : Back

1.4 : Top

1.5 : Bottom

1.6 : Left

1.7 : Right

The broken lines depict portions of the reservoir and drug delivery device that form no part of the claimed design.

1 Claim, 7 Drawing Sheets(56)
